UNITED STATES PATENT OFFICE.

JOHN S. NICHOLSON, OF PITTSBURG, PENNSYLVANIA.

PUZZLE.

No. 808,209.

Specification of Letters Patent.

Patented Dec. 26, 1905.

Application filed April 7, 1905. Serial No. 254,297.

To all whom it may concern:

Be it known that I, JOHN S. NICHOLSON, a citizen of the United States, residing at Pittsburgh, in the county of Allegheny and State 5 of Pennsylvania, have invented a new and useful Puzzle, of which the following is a specification, accompanied by drawings, in which—

Figures 1, 2, and 3 are side views of the blanks or surfaces of which the six-sided figure or puzzle is constructed. Fig. 4 is a top view of said six-sided figure or puzzle. Fig. 5 is a bottom view of said six-sided figure or puzzle.

My invention consists of a puzzle which is embodied in the putting together of a box, the same being capable of accomplishment only when the parts composing said box are placed in a certain peculiar relation to each other, which does not readily suggest itself 15 to a person attempting the feat. Thus my invention affords amusement and diversion and at the same time is instructive.

Referring to the drawings, 1 represents the blanks or surfaces of which the box is composed. Said blanks are rectangular in shape and are longer than wide, the excess length being turned up at each end along lines 2 to form wings 3, said wings 3 being folded diagonally at one corner thereof along lines 4 to 25 form locking-hooks 5. The portion of the blanks 1 which is included between the lines 2 is square and constitutes the surface which forms the sides of the box. Said square sur-

faces are folded diagonally along lines 6, the diagonal folds extending to the corners where 35 coincide lines 2 and 4 on the sides of said wings 3, where are disposed said locking-hooks 5. The folding of the blanks on the lines designated, as hereinbefore described, is not for the purpose of making permanent superim- 40 posed layers, but to produce creases which will act as hinges in putting the box together.

To put the box together, place the flap attached to the edge 7 18 underneath the edge 8 17, bend both sections on the crease 6, bringing the flap on 17 12 under the edge 18 15. Put the flap on the edge 14 16 of the remaining blank under the edge 7 9, bend down this blank over the flap on the edges 10 8 and 9 15, and tuck the flap attached to the edge 11 50 13 under the edge 10 12.

Having described my invention, what I claim as new, and desire to secure by Letters Patent, is—

A puzzle consisting of three rectangular 55 blanks, each blank comprising a square portion, creased diagonally, and two wings, each of said wings creased to form an angularly-disposed locking portion, said blocks being adapted to be put together to form a six-sided 60 box, substantially as herein set forth.

JOHN S. NICHOLSON.
